UNITED STATES PATENT OFFICE

2,545,719

TIMING MECHANISM

Reuben Wedeberg, Los Angeles, Calif., assignor to Stewart-Warner Corporation, Chicago, Ill., a corporation of Virginia

Original application May 17, 1946, Serial No. 670,467. Divided and this application March 3, 1948, Serial No. 12,807

9 Claims. (Cl. 161—1)

1

The present invention relates to timing mechanisms, and more particularly to an electrically operated timing mechanism which is adjustable to control the frequency and duration of energization of control circuits for intermittently operable appliances or systems.

One object of the invention is to provide a new and improved electrically operated timing mechanism for automatically controlling intermittently operable devices or systems.

Another object of the invention is to provide a timing mechanism for automatically controlling the duration of operation of intermittently operable devices or systems.

A further object of the invention is to provide a new and improved timing mechanism which is readily adjustable to vary the frequency of operation of intermittently operable devices or systems.

A still further object of the invention is to provide a timing mechanism which is readily adjustable to vary the duration of each period of intermittent operation of intermittently operable devices or systems.

It is also an object of the invention to provide a timing mechanism of generally improved construction which is simple and inexpensive to construct, assemble, and install, but which nevertheless is durable, reliable in operation, and readily adaptable to various uses.

More specifically it is an object of the invention to provide a timing mechanism having a cam assembly for controlling the frequency of operation which includes a cam disc of symmetrical profile and a masking disc therefor of irregular profile adapted to be angularly adjusted relative to the cam disc to mask the symmetrical profile symmetrically and thus provide for operation at regular intervals, and which timing mechanism also has a duration cam assembly that is adjustable to vary the duration of each period of operation of the controlled system or device.

Another object of the invention is the provision of a timing mechanism which includes adjustable frequency and duration cam assemblies, each of which operates switch means arranged in series with respect to each other and the energizing circuit of the controlled mechanism or system so that the controlled circuit is energized only when the cam assemblies operate to close both switches simultaneously.

Other objects and advantages of the invention will appear from the following description taken in connection with the drawings, in which:

Fig. 1 is a front elevation of the timing mechanism which is the subject of the invention;

Fig. 2 is a rear elevational view of the timing mechanism shown in Fig. 1;

Fig. 3 is a face view of a frequency cam disc of the type used in the timing mechanism of the

2

present invention, with a masking disc associated therewith in assembled relation;

Fig. 4 is a face view of the masking disc;

Fig. 5 is a face view of the duration cam disc for the timing mechanism and its masking disc in assembled relation;

Fig. 6 is a face view of the masking disc for the duration cam;

Fig. 7 is a sectional view taken diametrically through the frequency cam, the duration cam and their masking discs as assembled on their coaxial drive shafts; and

Fig. 8 is a schematic wiring diagram of an electrically operated system in which the timing mechanism of the present invention is adapted to be used.

The present application is a division of my co-pending application Serial No. 670,467, filed May 17, 1946, and entitled "Timing Mechanism." That application discloses an intermittently operating electrically controlled centralized lubricating system, operation of which is automatically controlled by a timing mechanism. The timing mechanism of the present invention is particularly adapted for controlling operation of a lubricating system of the type disclosed in the above mentioned application, but it is to be understood that it may be readily adapted to the control of various other controlled devices and systems, both in the lubrication field and elsewhere which are to be energized periodically for a predetermined interval of time particularly where it may be desirable to vary the frequency of energization or the duration of each period of energization of the controlled apparatus.

The general layout of the timing mechanism is shown in Fig. 1 wherein a base comprising a panel board 10 is shown for supporting the elements of the timing mechanism. Upon the back 40 of the panel 10 is secured an electric clock indicated at 12 in Fig. 2. The clock is driven by a synchronous motor of conventional construction which has the usual shafts 14 and 16 telescopically arranged as best seen in Figs. 1 and 7.

Preferably the shaft 14 corresponds to the hour hand shaft of a clock and for the purpose of this invention makes one revolution in twenty-four hours, while the shaft 16 corresponds to that which drives the minute hand of a clock and makes one revolution each hour. Instead of an hour hand, the shaft 14 carries a frequency cam disc 18 which determines the intervals or frequency at which the timing mechanism effects energization of the circuits controlled by it, and 50 instead of a minute hand the shaft 16 carries a duration cam disc 20 which determines the duration of the interval that the controlled circuits are energized. Each of these discs has peripheral notches or recesses for actuating electric 55 switches. Associated with the frequency cam 18

is a masking disc 19, while the duration cam 20 has associated with it a masking disc 21, these masking discs being adjustable to determine which of the recesses or notches of the cams shall be operative at any given time.

The frequency cam 18, as shown, has a symmetrical profile defining twelve notches or recesses 22 spaced at equal intervals to form symmetrically arranged dwells so that a stationary follower element cooperating therewith will be actuated every two hours as the cam 18 rotates. The masking disc 19 associated therewith is formed as shown in Fig. 4 with peripheral recesses irregularly arranged so that it can be adjusted with respect to the disc 18 and mask the symmetrical recesses 22 symmetrically to provide for operation of the system either at two hour intervals, at four hour intervals, at eight hour intervals, at twelve hour intervals, or only once in each twenty-four hours. If the controlled system is to be operated at two hour intervals, the masking disc 19, which is mounted coaxially with the disc 18, will be angularly adjusted so that its recesses register with all the recesses 22, but if operation at less frequent intervals is desired, the disc 19 may be shifted so that certain portions of its periphery will cover certain of the notches 22, leaving less than twelve of them effective for actuating the follower associated with the disc. As shown in Fig. 3, the disc 19 is adjusted to uncover only three of the notches 22, thus providing for operation of the devices or system controlled by the timing mechanism at eight hour intervals.

As shown in Fig. 7, the frequency cam disc 18 is rigidly secured to a hub 23 which is fixed to the hollow shaft 14 by a set screw 24. The masking disc 19 is rotatably mounted on the hub 23 but is held in face to face contact with the cam disc 18 by means of a coil spring 26 on the hub. A small boss or detent projection 29 on the face of the disc 19 is adapted to fit in any one of five openings 28 in the disc 18, which openings are marked respectively with the numerals 24, 12, 2, 8 and 4, as shown in Fig. 3, to designate the intervals at which the system will be operated when the masking disc is adjusted with its detent projection 29 in the respective openings. To facilitate such adjustment, the masking disc 19 is provided with diametrically projecting lugs 30 which may be grasped between the thumb and finger when it is desired to force the disc 19 away from the disc 18 (against the pressure of the spring 26) and thus release the projection 29 from the opening 28 in which it is engaged, so that the masking disc may be rotated to register the projection with another opening 28.

The duration cam disc 20, as shown in Fig. 5, has a series of peripheral notches or recesses 32 which differ in circumferential extent and are effective to limit operation of the controlled system or device, respectively, to periods of one to five minutes. In other words, a follower device on the switch which controls energization of the circuit of the controlled device or system drops into one of the notches 32 and the device or system continues to operate until the follower is cammed out of the notch. To determine which of the notches 32 shall be effective, the masking disc 21, which is associated with the cam disc 20, has a plain peripheral portion 34 and a single notch 31, which is of the same width as the widest of the notches 32. By rotative adjustment of the disc 21 with respect to the cam disc 20, this notch 31 may be registered with any of the sev-

eral notches 32 so as to expose a selected one of them while the plain circular portion 34 of the disc 21 covers the remaining notches 32.

For a special purpose, to be later explained, the masking disc 21 has an additional notch 35 with a leading edge 35a disposed diametrically opposite the middle of the notch 31. Opposite the notches 32 the cam disc 20 has a portion 37 of reduced diameter so as to expose or uncover the notch 35 at any of the several positions of adjustment of the masking disc with respect to the cam disc. At each of these positions of adjustment, the notch 31 is centered with respect to the notch 32 which it exposes; consequently the leading edge of the notch 35 is always disposed diametrically opposite the uncovered notch 32 so that the follower of a control device positioned to engage in the notch 35 will do so at the middle of the timing period represented by the active or exposed notch 32.

The cam disc 20 has an opening 38 opposite each of the notches 32 and the masking disc 21 has a small boss or projection 39 adapted to enter any one of the openings 38 when the disc 21 is suitably adjusted about its axis. As seen in Fig. 7, the disc 21 is fixed to a hub 33 by curling over the end of the hub, and the hub is secured to the shaft 16 by a set screw 51. A coil spring 36 on the hub presses the cam disc 20 into face to face contact with the disc 21. The cam disc is rotatable on the hub and is provided with radial lugs or finger pieces 40, by means of which it may be pulled forward out of contact with the disc 21, sufficiently to release the detent boss 39 from the opening 38 in which it is engaged so that the disc 21 may be rotated and the boss 39 brought into registry with another of the openings 38. In Fig. 5 the openings 38 are marked, respectively, 1—M, 2—M, 3—M, 4—M and 5—M to indicate that the notches will effect operation of the controlled device or system for periods of from one to five minutes, respectively, and as shown, the detent 39 is registered in the opening 38 corresponding to the three-minute period.

Since the cam discs 18 and 20 are similar in size and are secured in axially aligned closely spaced relation with the disc 20 and its masking disc 21 located in front of the frequency cam 18, means are provided for facilitating observation of the numbers on the frequency cam disc 18 so that the adjustment for frequency can be made readily. Preferably this means comprises segmental windows 41 and 42 in the discs 20 and 21, respectively, which may be registered with each other by rotating the discs with respect to each other. Thereafter they may be rotated together until the windows are brought opposite the openings 28 in the disc 18 as shown in Fig. 1. Since the openings 28 in the frequency cam 18 and the markings thereon will then be visible through the windows, the boss 29 on the masking disc 19 may be readily engaged in the desired opening 28 in the cam disc 18 after which the discs 20 and 21 may be adjusted relative to each other as desired.

In addition to the clock 12 and the timing cams just described, the panel 10 supports three switches 50, 52 and 54 suitably secured to the rear face of panel 10 as indicated in Fig. 1. Switch 50 has a follower arm 56 which engages upon the periphery of the frequency cam 18 while the switches 52 and 54 have followers 58 and 60, respectively, which engage the duration cam 20, the switches being so mounted that the cam is engaged at diametrically opposite points on its periphery as indicated in Fig. 1. These switches

control the supply of current to the circuits which are to be controlled, and for the purpose of illustrating the operation of my improved timing mechanism a schematic circuit diagram in which these switches are incorporated is shown in Fig. 8. This circuit is designed to control automatically the operation of the centralized lubricating system disclosed in my aforementioned copending application for patent. It is to be understood that the circuit is exemplary only of one adaptation of my timing mechanism to the control of a system and that the timing mechanism may be used for controlling various other electrically controlled systems or devices.

In Fig. 8 lead wires 62 and 64 designate the source of current supply which is controlled by a manually operated master switch 66. The clock and the frequency and duration cam assemblies along with the switches operated thereby are designated by the same numerals as previously used to designate these parts. At 68 a solenoid operated valve for controlling the flow of air under pressure to the air motor of a lubricant compressor is indicated diagrammatically while the numbers 70 and 74 designate a pair of dia-grammatically shown solenoid operated reversing valves between the lubricant compressor and the conduit system of the lubricating system.

The function of the timing mechanism and the solenoid operated valve 68 is to initiate operation of the lubricant compressor at predetermined intervals and then to maintain such operations for a predetermined period of from one to five minutes while the purpose of the solenoid operated valves 70 and 74 is to reverse the flow of lubricant through the lubricating system when a circuit through the system is completed in one direction.

Whenever the master switch 66 is closed the clock motor 12 is energized from the leads 62 and 64 through conductors 78 and 80 and drives the frequency cam 18 and the duration cam 20 for as long as the switch 66 remains closed. As a result, the follower 56 on switch 50 will be brought into engagement with the exposed recesses 22 in the cam 18 with a frequency determined by the setting of the masking disc 19. When the follower drops into a recess it moves to close a contact 82 in the switch 50. This contact is connected by a conductor 84 to a contact 86 in switch 52. Since the frequency cam can be set to become effective at intervals of two or more hours, and the duration cam is driven by the clock motor 12 at a speed to bring its exposed recess 32 to effective position once every hour, these cams and their masking discs can be readily adjusted so that the duration cam will become effective to close the switch 52 whenever the frequency cam becomes effective to close switch 50 irrespective of the number of hours between closings of the latter switch.

Closing of the switch 52 completes a circuit from the contact 86 to the solenoid operated valve 68 by way of a conductor 88 and thence back to the main lead wire 62. Since the switch 50 is connected to the other main lead wire 64 by a conductor 90, a circuit is energized which includes the main lead wire 64, conductor 90, switch 50, contact 82, conductor 84, contact 86, switch 52, and conductor 88 leading to the solenoid operated valve 68. The other side of this valve is connected to the other lead wire 62 by a conductor 92 so that the solenoid operated valve is energized and initiates operation of the lubricant compressor which it controls.

The switch 52 is also connected by a conductor 94 to the third switch 54; and, since the follower

60 of this switch will be riding on the periphery 34 of the duration cam masking disc at the beginning of the period controlled by this cam, the movable contact of this switch will be held in a position to engage a contact 96 in this switch. This contact 96 is connected by a conductor 98 to one side of the solenoid operated reversing valve mechanism 70. The circuit for the latter is completed by conductors 104 and 106, the latter being connected to lead wire 62. Energization of the solenoid operated valve 70, which will occur simultaneously with opening of the solenoid operated valve 68 for the compressor, causes the lubricant pumped by the compressor to flow in one direction through the conduit system to the various bearings to be lubricated.

The time required for the lubricant to make a complete circuit of a conduit system can be determined and the recesses 32 in the duration cam 20 may be so constructed that by the time this has occurred the duration cam will have been advanced by the clock sufficiently so that the follower 58 on switch 52 will be at the midpoint of the notch 32 with which it happens to be engaged. Since the edge 35a of the notch 35 in the duration cam masking disc is diametrically opposite the midpoint of the notch 31 in this disc, and the follower 58 of switch 52 is diametrically opposite the follower 60 of switch 54, the follower of this latter switch will drop into notch 35 at the time cam 20 has advanced to the point where follower 58 is at the midpoint of notch 32. By proper adjustment of the masking discs for the cams this may be made to coincide with the time that it takes lubricant to make a circuit of the conduit systems in one direction as will be understood.

Thereupon the arm of switch 54 will be shifted from contact 96 to a contact 108 which is connected by a conductor 110 to one side of the second solenoid operated valve 74. The circuit for this solenoid back to the lead wire 62 is completed through a conductor 116 and conductor 106. Separation of the arm of switch 54 from contact 96 will deenergize solenoid 70 and the engagement of the arm of this switch with contact 108 energizes the circuit for the solenoid 74. This effects a reversal in the position of the two valves and a resulting flow of lubricant through the conduit system in a direction opposite to that in which it had been flowing.

The continued rotation of the duration cam disc 20 by the motor 12 will carry the notch 32 past the follower 58, and the notch 35 past the follower 60, so that the followers engage upon the periphery of their respective cams and masking discs. This opens the circuit to the solenoid operated valve 68 which controls operation of the compressor motor, and to the solenoid operated reversing valves 70 and 74 so that operation of the compressor is discontinued and no lubricant is delivered to the conduit system.

As long as master switch 66 is closed, the clock motor 12 will continue to rotate and will rotate the cam discs 18 and 20 so that the frequency disc 18 will eventually be turned far enough to carry the notch 22 in which the follower 56 of switch 50 happens to be engaged, past the follower, so that the latter will thus ride upon the periphery of the cam disc, thus moving the arm of switch 50 sufficiently to open the circuit through contact 82. Thereafter the lubricating system cannot again be energized until the frequency and duration cams have been rotated far enough by the clock motor to bring the followers 56 and 58 into engagement with exposed notches in their

respective cams at the same time, and the frequency at which this occurs will of course depend on the setting of the masking disc for the frequency cam.

From the above description of the application of my improved timing mechanism to the control of a centralized lubricating system, it will be understood that the mechanism may be readily adapted to the control of other systems, devices or appliances which are to be operated intermittently, particularly where it is desired to have a timing mechanism that can be adjusted to vary the time between periods of operation and also the duration of each period of operation. Almost unlimited variation in the sequence of operation of the devices controlled by the timing mechanism can be secured by the proper arrangement of the notches 22 and 32 in the frequency and duration cams 18 and 20, and the notches in their masking discs, and then varying the setting of these discs as required.

It will also be recognized that while there is shown and described herein certain structure embodying the invention and illustrative thereof, the invention is not limited to the specific forms shown but embraces all changes and modifications in its various features and all equivalents thereof coming within the scope of the appended claims.

I claim:

1. In a timing mechanism, the combination comprising coaxially mounted front and rear cam discs, a masking disc for each of said cam discs adapted to be disposed in contacting engagement with the rear face thereof, said cams and masking discs being rotatably adjustable with respect to each other, means for detachably fixing the rear cam and its masking disc against relative movement including a series of closely grouped detent apertures in said rear cam disc and a detent projection on said rear cam masking disc engageable selectively in said apertures by rotative adjustment of said cam and masking disc and visible through the aperture in which it is engaged, and registerable window apertures in said front cam and its masking disc adjustable by rotation of said discs to align said windows with each other and with series of apertures in the rear cam for observation therethrough, thereby to facilitate adjustment of the masking disc for said rear cam.

2. In a timing mechanism, a cam disc having a peripheral cam outline, a masking disc therefor, a hub to which one of said discs is fixed and upon which the other disc is rotatably adjustable, one disc having a series of detent apertures and the other disc having a detent projection adapted to engage selectively in said apertures, a spring on said hub to press said discs yieldingly in face to face contact to retain said projection in a selected aperture, radial arms extending from the rotatably adjustable disc beyond the peripheral outlines of both discs to facilitate manual manipulation of the disc in adjusting it.

3. In a timing mechanism, a clock, a frequency cam assembly driven by said clock including a cam disc having a profile defining symmetrical arrangement of cam dwells and a masking disc, said discs being angularly adjustable relative to each other and said masking disc having an irregular profile including a series of dwells adapted at one position of adjustment of said discs to register with all the symmetrically arranged dwells and at other positions of adjustment to register with a symmetrically arranged number of dwells in the cam disc greater than one and less than all, re-

leasable means for fixing said discs against relative movement including a detent on one disc and a series of apertures in the other arranged to receive said detent for fixing said discs against relative movement at the aforementioned position, a hub fixed to one of said discs, the other of said discs being rotatable on said hub, spring means on the hub for holding the discs in face-to-face contact and the releasable detent in disc fixing positions, and one or more radial arms on the disc rotatable on said hub to facilitate manual manipulation of the disc for adjusting the same.

4. In a timing mechanism, a clock, a duration cam disc driven thereby and having a series of circumferentially spaced apart peripheral recesses differing from each other in angular extent, a masking disc carried with said cam disc, said discs being rotatably adjustable with respect to each other and said masking disc having a peripheral recess at least equal in angular extent to the longest of the recesses in the duration cam whereby said masking disc may be adjusted to expose any selected one of said recesses of the duration cam, and detent means to retain the masking disc at each of such positions of the adjustment, said duration cam having an additional peripheral recess of angular extent at least equal to the total angular portion of the cam disc occupied by its said series of recesses, and the masking disc having a recess so positioned that one end of said recess is diametrically opposite the middle of any recess of the duration cam which the masking cam is adjusted to expose.

5. In a timing mechanism, a clock, a duration cam disc driven thereby and having a series of circumferentially spaced apart peripheral recesses differing from each other in angular extent, a masking disc carried with said cam disc,

40 said discs being rotatably adjustable with respect to each other and said masking disc having a peripheral recess at least equal in angular extent to the longest of the recesses in the duration cam whereby said masking disc may be adjusted to expose any selected one of said recesses of the duration cam, and detent means to retain the masking disc at each of such positions of the adjustment, said duration cam having an additional peripheral recess which has an angular extent at

45 least equal to the total angular portion of the cam disc occupied by its said series of recesses, and the masking disc having a second recess so positioned that the one end of it is diametrically opposite the middle of its first mentioned recess.

55 6. A timing mechanism for controlling operation of intermittently operable devices or systems comprising a frequency controller including relatively adjustable cam and masking discs, one of which has a plurality of symmetrically arranged

60 peripheral recesses and the other of which has peripheral recesses so arranged that at one position of relative adjustment of the discs one recess is unmasked and at other positions of adjustment a plurality of recesses are unmasked in

65 symmetrical arrangement, a duration controller including relatively adjustable cam and masking discs having nonsymmetrically arranged recesses of varying angular extent including first and second recesses in said masking disc and a plurality of recesses of varying angular extent individually unmasked by the said first recess in said masking disc upon selective adjustment of the latter and a single recess in said cam disc of sufficient angular extent to unmask the said second recess in said masking disc whenever the masking disc is

at a position of adjustment at which the first recess therein unmasks one of said plurality of recesses in said cam disc, means to lock said cam and masking discs at desired positions of adjustment effective to cause said discs to rotate together, and means for driving said frequency and duration controllers at different but correlated speeds.

7. A timing mechanism for controlling operation of intermittently operable devices or systems comprising a frequency controller including relatively adjustable cam and masking discs, one of which has a plurality of symmetrically arranged peripheral recesses and the other of which has peripheral recesses so arranged that at one position of relative adjustment of the discs one recess is unmasked and at other positions of adjustment a plurality of recesses are unmasked in symmetrical arrangement, a duration controller including relatively adjustable cam and masking discs having nonsymmetrically arranged recesses of varying angular extent including first and second recesses in said masking disc and a plurality of recesses of varying angular extent individually unmasked by the said first recess in said masking disc upon selective adjustment of the latter and a single recess in said cam disc of sufficient angular extent to unmask the second recess in said masking disc whenever the masking disc is at a position of adjustment at which the first recess therein unmasks one of said plurality of recesses in said cam disc, said second recess in the masking disc in said controller having one end which falls diametrically opposite the mid point of its first recess, means to lock said cam and masking discs at desired positions of adjustment effective to cause said discs to rotate together, and means for driving said frequency and duration controllers at different but correlated speeds.

8. In a timing mechanism a duration controller comprising a cam disc having a series of circumferentially spaced apart peripheral recesses of varying angular extent, a masking disc having a first peripheral recess at least equal in angular extent to the longest of the recesses in said duration cam, said cam and masking disc being selectively adjustable to positions at which the series of recesses in said cam disc are individually unmasked by the said recess in said masking disc, a recess in said cam disc independent of the series of recesses therein and of angular extent at least equal to the angle through which the masking disc must be moved to unmask the recesses on the opposite ends of said series, a second

recess in said masking disc having one end diametrically opposite the mid point of its first recess, said second recess coinciding with a portion of the said independent recess at all positions of selective adjustment of said discs, means to drive said cam disc and means on the confronting faces of said discs for locking said masking disc at said selective positions of adjustment effective to cause said masking disc to rotate with said cam disc including a projection on said masking disc diametrically aligned with the said end of said second recess, and apertures in said cam disc diametrically aligned with the mid point of said plurality of recesses in said cam disc adapted to receive said projection.

9. In a control system, a frequency controller including a pair of discs having peripheral recesses to define cam dwells, said discs being relatively adjustable to bring the recesses therein into and out of coincidence for rendering the same effective, a duration controller including a pair of discs having peripheral edges containing recesses of different effective lengths, said discs being relatively adjustable to bring the recesses therein into and out of coincidence and thereby individually to unmask the recesses of different effective lengths, and a second recess having a leading edge diametrically opposite the mid point of the first of said recesses which is unmasked, a source of electrical energy, a first switch operated by the recesses in said frequency controller, a second switch operated by the recesses of different effective length in said duration controller, a circuit including said two switches and said energy source in series, and a third switch in said circuit in series with said first and second switches and having a pair of contacts adapted to be connected to a controlled mechanism, said third switch being operated by said second recess in the duration controller to open one of the contacts to which it is connected and close the other at the mid point in the effective period of said first recess.
